US00D836383S

(12) **United States Design Patent** (10) Patent No.: **US D836,383 S**
(45) Date of Patent: **** Dec. 25, 2018**

(54) **ELECTRIC FRYER**

(71) Applicant: **SEB**, Selongey (FR)

(72) Inventor: **Laurent Dutruel**, Dole (FR)

(73) Assignee: **SEB**, Selongey (FR)

(**) Term: **15 Years**

(21) Appl. No.: **29/621,372**

(22) Filed: **Oct. 6, 2017**

Related U.S. Application Data

(62) Division of application No. 29/546,775, filed on Nov. 25, 2015, now Pat. No. Des. 819,389.

CLAIM

The ornamental design for an electric fryer, as shown and described.

DESCRIPTION

FIG. 1 is a perspective view of an electric fryer showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top view of the electric fryer thereof; and,

FIG. 7 is a bottom view of the electric fryer thereof.

The broken lines are shown for the purpose of illustrating parts of the electric fryer that form no part of the claimed design.

1 Claim, 7 Drawing Sheets
